WILLIAM R. MALONE, OF MASON CITY, WEST VIRGINIA.

Letters Patent No. 83,295, dated October 20, 1868.

IMPROVEMENT IN SAFETY-VALVE.

The Schedule referred to in these Letters Patent and making part of the same.

To all whom it may concern:

Be it known that I, WILLIAM R. MALONE, of Mason City, in the county of Mason, and State of West Virginia, have invented a new and useful Improvement in Safety-Valves for Steam-Boilers; and I do hereby declare that the following is a full, clear, and exact description thereof, which will enable others skilled in the art to make and use the same, reference being had to the accompanying drawings, forming part of this specification, in which—

Figure 1 represents a horizontal sectional elevation of a boiler with my improvement attached, and

Figure 2 represents a transverse section of the same.

Similar letters of reference indicate like parts.

The object of this invention is to provide a means for automatically checking the increase of steam in the boilers when the desired amount of pressure has been raised.

It consists in an arrangement of devices for conveying the steam or water which escapes through the safety-valve, into the fire, for checking it, whereby the increase of steam is checked.

A represents a steam-boiler, and B the safety-valve, which is provided with a tube, running into the boiler sufficiently to pass below the water-level.

D represents a tube connecting with the safety-valve, and communicating with the furnace, as shown in dotted lines in figure, whereby the water or steam thrown

off through the safety-valve, while the pressure of steam is greater than required, may be thrown upon the fire, and suddenly, thereby, check it, to the extent that the steam will fall to the required pressure, when the flow of water on the fire will stop.

I propose, also, to confine the safety-valve lever and weight within a lock-up case, whereby the control of the same is taken out of the hands of the engineer entirely.

Other pipes may also be attached, for receiving the escaping steam or water, and conveying it to any part of a building or steamboat, for extinguishing fires.

The tube C is screwed through the boiler-sheet, and into the safety-valve tube, thus making a steam-tight joint without the aid of packing, as ordinarily used for connecting safety-valves.

Having thus described my invention,
I claim as new, and desire to secure by Letters Patent—

The arrangement of the safety-valve B, exhaust-pipe D, provided with pipe-connections communicating with the furnace, the extension-tube C, and boiler A, substantially as described.

WM. R. MALONE.
